UNITED STATES PATENT OFFICE.

WILL T. KRAUSE, OF DINUBA, CALIFORNIA.

PUMP.

1,305,290.

Specification of Letters Patent. Patented June 3, 1919.

Application filed May 10, 1918. Serial No. 233,739.

To all whom it may concern:

Be it known that I, WILL T. KRAUSE, a citizen of the United States of America, residing at Dinuba, in the county of Tulare and State of California, have invented certain new and useful Improvements in Pumps, of which the following is a specification.

This invention relates to pumps of the centrifugal or impeller type of a character 10 adapted to be suspended in well casings, the movable member of which rotates in a horizontal plane and acts to force the water upwardly through the well casing.

The present invention provides a pump of 15 this character possessing several important advantages, in that it embodies a self contained structure adapted to be lowered into a conventional well casing and adapted to form a substantially fluid tight joint therewith at any desired point in the height of the well casing, such point being determinable from the surface of the ground, so that the pumps may be utilized in well casings 20 that are already in place.

25 A further object of the invention is to provide a pump of this character discharging at a plurality of points about the periphery of the impeller whereby resistance to the movement of the water is decreased, while 30 at the same time the impeller is protected to a material extent from the back wash or thrust of the column of water thereabove.

Further objects and advantages of the invention will be set forth in the detailed description which now follows.

In the accompanying drawings:

Figure 1 is a vertical sectional view illustrating one type of pump embodying the principles of the invention.

40 Fig. 2 is a horizontal sectional view upon line 2—2 of Fig. 1.

Fig. 3 is a horizontal sectional view upon line 3—3 of Fig. 1.

Fig. 4 is a horizontal sectional view upon 45 line 4—4 of Fig. 1.

Fig. 5 is a vertical sectional view illustrating a slightly modified form of the invention, and,

Fig. 6 is a horizontal sectional view upon 50 line 6—6 of Fig. 5.

Like numerals designate corresponding parts in all of the figures of the drawings.

Referring to the drawings and particularly to Figs. 1 to 4, inclusive, 5 designates a 55 well casing of conventional form. It will be noted that one of the important features of

the invention is that this casing is caused to serve both as a suction and discharge pipe for the pump. The pump proper comprises a cylinder 7 having a bottom 8 that is provided with an intake collar 9. Secured to the walls of this cylinder by ears 10 is a horizontal plate 11 of smaller diameter than the cylinder, which lies in spaced relation to the bottom 8 and provides a chamber 12 60 within which the impeller or runner 13 is mounted for rotation. The impeller is provided with blades 14 that are of such shape as to throw the water outwardly when the impeller is rotated. Rotation of the impeller 70 is effected by shafts 15 and 16 that are preferably connected by a universal joint 17. The shaft 15 has a bearing at 18 in the plate 11 and the shaft 16 is preferably suspended upon a thrust bearing such as that indicated 75 at 19 in Fig. 5 by which bearing the shafts 15 and 16 and the impeller are held in such suspension as to relieve all friction between the bottom of the impeller and the plate 8.

The impeller comprises the top plate 13^a, 80 bottom plate 20 and an intake collar 21 which projects through the collar 9 of the plate 8, it being understood that the blades 14 are disposed between the plates 13^a and 20. A ring 22 is secured by screws 23, or 85 other suitable fastening devices, to the plate 8 and this ring in turn has secured thereto by screws 24, or other suitable fastening devices, a leather or other flexible packing ring 25. Strips 26 having out-turned lower ends 90 27 project beneath a spread-ring 28, which has its outer face inclined at 29. Suspension rods 30 have their lower ends engaged with ears 31 formed upon the spread-ring 28 and the upper portions of these suspension rods 95 pass through brackets 32 that may be supported in any desired way or in any desired position adjacent the top of the well casing. I have in the present invention shown them as being carried by a ring 33. 100

When the pump is lowered into the well, the rings 22 and 28 move downwardly together until the suspension rods 30 reach the limit of their movement or until the angular ends 34 of said rods engage the ears 32, 105 whereupon further downward movement of the suspension rods is rendered impossible and the ring 28 is brought to a stop. However the cylinder 7 and associated parts may continue their downward movement to such extent as to forcibly jam the packing ring 25 between the inclined face 29 of the ring 110

28 and the adjacent part of the well casing 25, to thereby form a fluid tight joint at this point. It will thus be seen that the present structure provides means for securing a 5 tight joint between the pump and the well casing at any desired point, this point being determined by the length of the rods 30. This structure provides means, controllable from accessible positions at the top of the 10 well casing for securing such fluid tight joint at any desired point in the height of a well casing already in position. The strips 26 hold the rings 22 and 28 in assembled position with respect to each other, during 15 the time that the pump is being lowered into the well, but prevent undue separation of these rings and insure that the structure, as a whole will be easily and gently lowered to operative position.

20 In the form of the invention illustrated in Figs. 5 and 6, the parts are substantially like those heretofore described, and in so far as the parts are the same, the same reference numerals have been applied. However 25 in this case the means for forming a tight joint between the pump proper and the well casing 5, comprises a fixed ring 40 that is secured in the well casing at the point at which it is desired to locate the pump. A 30 packing ring 41 of leather, rubber or other suitable material is carried by the bottom plate 8 of the cylinder and rests upon and forms a tight joint upon the ring 40. It is to be noted that in both forms of the in- 35 vention, the weight of the pump is utilized to secure the fluid tight joint, the weight of the pump, in the structure illustrated in Fig. 1, acting to jam the ring 25 between the inclined face 29 and the casing 5 and 40 the weight of the pump in the structure illustrated in Fig. 5 serving to jam the ring 41 between the ring 40 and the underside of the cylinder.

The operation of the device is as follows:

- 45 Rotation being imparted to the impeller, water flows upwardly through the suction portion 5^a of the casing 5, through the intake collar 21 of the impeller, and is thrown outwardly by the blades of the impeller. 50 Water discharged at the periphery of the impeller passes upwardly through the space formed between the edge of the plate 11 and the wall of the cylinder 7, it being apparent from an inspection of Fig. 4 that this plate, 55 11 is materially smaller in diameter than the interior of the cylinder 7, so that the discharge ports 42 are made of considerable area and extend entirely around the edge of the plate 11 except at those points where 60 the ears 10 are located. Consequently the resistance to the discharge of the water is decreased and the plate 11 relieves the impeller to a considerable extent of the weight of the column of water thereabove, the central 65 trifugal action due to the rotation of the

top plate 13^a of the impeller tending to throw the water from beneath the plate 11 and acting, as before stated, to relieve the top plate of the impeller of some of the weight of the water thereabove. 70

Where pumps of this type are provided with a single discharge outlet, the choking of the outlet tends to decrease the efficiency of the pump. It will be noted that in the present case, the impeller discharges at substantially all points and water friction is thereby largely eliminated. 75

From the foregoing description it will be seen that simple and efficient means are herein provided for accomplishing the objects of the invention. It is to be understood however that the invention is not limited to the precise construction set forth, but that it includes within its purview whatever changes fairly come within the spirit of the appended claims. 80

Having described my invention what I claim is:

1. The combination with a well casing, of a cylinder of substantially equal diameter to the casing, a plate disposed in said cylinder and of smaller diameter than the cylinder to thereby leave a discharge outlet about the edge of the said plate, a rotary impeller mounted beneath said plate and within the cylinder and an intake collar carried by the impeller and journaled centrally in the bottom of said cylinder. 90

2. In a device of the character described, a cylinder having a rotary impeller mounted therein, a compressible packing member carried thereby, a spreader ring, means for holding the cylinder and spreader ring in predetermined relation during the time that they are lowered into a well, means for holding the spreader ring against downward movement after a predetermined downward movement of the same, and means upon said spreader ring coacting with the packing member to force the latter against the face of the well casing upon continued downward movement of the pump cylinder after the movement of the spreader ring ceases. 105

3. The combination with a well casing, of a pump structure adapted to be lowered thereinto, a packing ring carried by the pump structure, a spreader ring, means for permitting a limited downward movement of the spreader ring and for then holding said spreader ring against further movement and a packing ring disposed between the pump structure and the spreader ring, and expanded by the weight of the pump upon continued downward movement of the pump after the movement of the spreader ring ceases, said packing ring acting against said spreader ring. 115

4. The combination with a well casing, of a pump cylinder of cup like formation adapted to fit snugly therein, a bottom in said cyl- 120 125 130

- inder having a central opening, a depending packing ring carried by the pump cylinder, a spreader ring having an inclined outer face, clips engaging the spreader ring and 5 the pump cylinder but preventing complete separation of these members, vertically extending members connected to the spreader ring and adapted to hold the spreader ring against downward movement after a predetermined downward movement of the same 10 and an impeller disposed in the cylinder and having a central intake collar projecting through the opening in the bottom of the pump cylinder.
- 15 5. The combination with a well casing of a pump cylinder of cup like formation of such size as to fit snugly therein, a plate disposed horizontally in said cylinder and of smaller diameter than the cylinder to there- 20 by leave a discharge outlet about the edge of the plate, a rotary impeller disposed beneath said plate, an intake collar upon the impel- ler projecting through the bottom of the
- pump cylinder, a ring carried by the bottom of the pump cylinder, a flexible packing ring 25 carried by the first named ring, a spreader ring with which the packing ring coacts, vertically extending rods by which the spreader ring is supported and means for permitting a limited downward movement 30 of said rods and preventing their further movement after such limited downward movement.
6. The combination with a well casing of a pump structure comprising two parts 35 connected to be lowered together into the well casing but capable of limited relative movement, means for holding one of said parts against further movement after a predetermined downward movement into the 40 well casing and means operable under the weight of the pump and acting against the said held part to form a fluid tight joint with the wall of the casing.

In testimony whereof I affix my signature. 45
WILL T. KRAUSE.
